UNITED STATES PATENT OFFICE.

JOHN K. SAX, OF PITTSTON, PENNSYLVANIA.

IMPROVEMENT IN CASTING CAR-WHEELS.

Specification forming part of Letters Patent No. 152,011, dated June 16, 1874; application filed April 15, 1873.

To all whom it may concern:

Be it known that I, JOHN K. SAX, of Pittston, in the county of Luzerne and State of Pennsylvania, have invented certain new and useful improvements in the Manufacture of Railway-Car Wheels and Molds therefor, of which the following is a specification, reference being had to the accompanying drawings, in which—

Figure 1 is a top view of the flask and mold made use of. Fig. 2 is a side view or elevation of the same. Fig. 3 is an enlarged view of the same in vertical cross-section through the plane indicated by the dotted line $x\ x$. Fig. 4 is a view in vertical central cross-section of the metallic band made use of to keep separate the two kinds or qualities of metal of which the wheel is made while they are being cast. Fig. 5 is an enlarged view of the flask and mold (shown in Figs. 1, 2, and 3) in central vertical transverse section through the plane indicated by the dotted line $x'\ x'$ in Fig. 1. Fig. 6 is a top or plan view of the lower part or "drag" of the flask. Fig. 7 is a vertical sectional view of a part of the drag (shown in Fig. 6) on the line $x^2\ x^2$, looking in the direction indicated by the arrow. Fig. 8 is a top view of the lifting-frame, by means of which the band (shown in Fig. 4) is held in the matrix of the mold, and lifted therefrom at the proper time. Fig. 9 is a top view of the central cap of the flask. Fig. 10 is a view of the same in vertical cross-section on the line $x^3\ x^3$. Fig. 11 is a top view of the exterior cap-ring of the flask.

This invention consists in a process for producing a railway-car or locomotive wheel, having a body or center of one kind or quality of metal—as tough cast-iron—and a tread or tire of another kind or quality of metal—as steel or hard cast iron—both metals being cast into the same mold at the same time, and left in direct contact to cool and amalgamate.

The letter a indicates the bottom board, upon which the mold and flask sit; b , the lower part or drag of the flask, and b^1 the exterior cap of the flask, which I will call the "body-ring," fitting to the drag by dowel-pins b^4 , as is usual. The drag b has, or well may have, radial arms or spokes b^5 , preferably three in number, which run to a central ring, b^6 , their upper outline conform-

ing to the contour of that side of the wheel which is undermost, but these spokes do not touch the wheel when it is cast. The letter c indicates the molding-sand in the drag. Each of the spokes b^5 has a round pillar, b^7 , projecting upward, its top just even with the upper face of the wheel that is to be cast in the mold, such pillars running through corresponding holes in the plate of the wheel, and each surrounded with molding-sand appertaining to the sand in the drag. Starting from under the bottom of each of the spokes b^6 , a bolt, d , headed at the bottom, runs up through each of the pillars b^7 , and thence to the level of the top of the flask, or just a little above that level, to serve as guides and connections for the central-cap portion of the flask, as will be herein-after described.

The body-ring b has numerous flukes or wings b^8 , extending inward, and conforming to the contour of the tread of the wheel, but not touching it. The letter e' indicates the sand pertaining to this body-ring. The central cap of the flask is composed of the central ring e , the radial arms e^1 , the cross-flukes e^2 , and the shorter radial arms e^3 . The lower outline of the whole central cap conforms to the contour of the upper face of the wheel, but does not touch it. This central cap rests upon the pillars b^7 by means of the pillar-points b^4 , corresponding to the pillars b^7 . The central cap is guided to its place by the bolt-rods d , running up, through the enlargements e^4 , to the top of the cap; and the central cap and drag are held together, when the casting is made, by the nuts d^1 on the upper ends of the bolts d . The letter e^2 indicates the sand pertaining to the central cap.

It will be observed that there is an annular opening, s , all around the mold between the sand pertaining to the body-ring and the sand pertaining to the central cap.

The letter m indicates the core for forming the hole in the hub of the wheel, for the reception of the axle. The letter n indicates the space in the matrix of the mold for the reception of the metal of which the body of the wheel is to be cast, which metal may well be poured through the sprues $n'\ n'$, which sprues may be located at any desirable and suitable points within the band o .

The letter *i* indicates the space in the matrix of the mold to be filled with the metal that forms the tread of the wheel, and which is, by preference, poured through the sprues *i*¹ *i*¹, communicating at the bottom with a runner-channel, *i*², scooped out in the surface of the sand pertaining to the drag, and running entirely around the mold, from which runner-channel numerous small sprues *i*³ enter the matrix of the mold outside the band *o*.

The band *o* may be made of iron or steel—possibly of some other material; and may extend from the bottom of the matrix to the top, or to the point indicated in the drawings, or to any other desired and suitable height. The band *o* is introduced into the mold through the annular opening *s*, and is suspended by means of the rods *o*¹ which are fastened into the lifting-frame, which is composed of the ring *o*², the arms *o*³, and the guides *o*⁴, fitting upon the outside of the body-ring *b*¹. On the inside of the ring *o*² are mortised lugs *o*⁵, having set-screws *o*⁶ running into the mortises, by means of which set-screws the rods *o*¹ are fastened to the lifting-frame. I prefer to form the body *n* of the wheel of soft cast-iron and the tread *i* of hard cast iron or steel, though steel or iron may be used for one or the other, or both, as is desirable. The annular opening *s* is formed by a band on the pattern. After the mold has been rammed up and the pattern withdrawn the central cap is fastened to the drag by the nuts *d*¹. The band *o* is inserted and the wheel is ready for the casting.

The metal for the body and the metal for the tread are both poured at or about the same time, and in case the band *o* does not extend to the top of the matrix, the pouring of the metal for the tread ceases when the metal arrives at the top of the band. The rise of the

metal on both sides of the band can be readily seen through the opening *s*. The metal may be poured until the opening *s* is filled so as to form a head for the metal in the wheel.

Before the two metals solidify the band *o* may be removed by raising up the lifting-frame, leaving the two metals in direct contact, so that they will intimately mix, amalgamate, and weld together. If a head is allowed to form in the opening *s*, that is cut off afterward.

The wheel represented is what is known as a plate-wheel, and needs to have holes through it for the pillar-supports *b*⁷. In casting a spoke-wheel these supports run between the spokes.

This process and apparatus is as readily applicable to the production of a locomotive driving-wheel as to the making of a car-wheel.

So far as the mold described and the product of this process are concerned, both are reserved for subject-matter of other Letters Patent.

I claim as my invention—

The process of casting the body of a car or engine wheel of one kind or quality of metal, as soft cast-iron, and the tread or tire of another kind or quality of metal, as hard cast-iron or steel, in the same mold, and at the same time, by means of an annular band interposed within the mold between the two metals, which band is afterward withdrawn, so as to leave the two metals while still fused in immediate contact, so that they will well weld or fuse together, the same being done substantially as described, and for the purpose set forth.

JOHN K. SAX.
